UNITED STATES PATENT OFFICE.

EDWARD J. GULICK, OF ELKHART, INDIANA, ASSIGNOR TO C. G. CONN, LTD., OF ELKHART, INDIANA, A CORPORATION OF INDIANA.

DIE FOR MAKING VALVE-CASINGS FOR WIND-MUSICAL-INSTRUMENT VALVES.

1,345,921.

Specification of Letters Patent.

Patented July 6, 1920.

Application filed October 28, 1918. Serial No. 260,010.

To all whom it may concern:

Be it known that I, EDWARD J. GULICK, a citizen of the United States, residing at Elkhart, county of Elkhart, Indiana, have 5 invented certain Dies for Making Valve-Casings for Wind-Musical-Instrument Valves, of which the following is a specification.

This invention relates to dies or devices 10 for making a one piece valve casing for wind musical instrument valves of the horn or cornet type, although the invention may be used for making valve casings for all wind musical instrument valves of the piston type.

Heretofore valve casings of the general character herein described have been made of two or more separate pieces of metal 20 separately machined or finished in a lathe and thereafter permanently joined together by welding, brazing, screw threads, or otherwise, which method and structure is complicated, expensive and not always productive of the best results.

25 The object of my invention is the production of dies or devices whereby a metal valve casing for cornets, and the like, may be formed from a single piece of ductile tubing, thereby simplifying and expediting the 30 casing construction as well as effecting a great reduction in the cost thereof.

On the drawing, Figure 1 is a side elevation of a cornet showing my improved valve casing applied thereto; Fig. 2 is a section 35 taken longitudinally through my improved valve casing; Fig. 3 is a top plan view of the dies and die box; Fig. 4 is a section in elevation through the dies and die box showing the valve casing expanded by the arbor 40 member; Fig. 5 is a fragment showing the same members prior to the introduction of the expanding arbor; Fig. 6 is a view of the valve casing body prior to die introduction; Fig. 7 is a top plan view of the thread forming die; and Fig. 8 is a section taken on the line 8—8 of Fig. 7. Similar numerals 45 of reference indicate like members and parts of members throughout the several views on the drawing.

50 Referring to the drawing in detail, the numeral 1 indicates a wind musical instrument of the cornet type in which the valve casing 2 is shown partially in section and within which a piston valve 3 is arranged.

55 The numeral 4 indicates a valve casing cap

which may be screw threaded upon the upper end of the casing 2 and is suitably apertured to permit the passage of the valve stem 5 which is adapted to carry the usual presser key 6.

60 My improved dies or devices enable the construction of a valve casing from a single piece of ductile metal tubing, usually brass, of substantially uniform diameter. At Fig. 2 of the drawing a finished one piece valve 65 casing is illustrated, wherein the numeral 7 indicates the cylindrical valve chamber connected with the enlarged portion 8 the bore whereof is somewhat larger than the bore of the portion 7, the end of the portion 8 being exteriorly screw threaded at 9 to receive the threaded cap member 4. The numeral 10 indicates a shoulder formed at the junction of the different casing bores which is adapted to serve as a seat for the 70 prongs of the valve spring seat (not shown) which is well known in the art. The numerals 11, 11 indicate a plurality of air 75 passages formed in the casing portion 7 which are adapted to be placed in communication with the main cornet air passages and with which the piston valve passages (not shown) are adapted to register.

80 Numerals 12 and 13 indicate a pair of co-operating half die members removably and 85 adjustably arranged within the die box 14 and adapted to be rigidly held in co-operation by the set screws 15, 15 mounted in the box member. The die members 12 and 13 are formed with co-operating semi-cylindrical bores 16 and 19, respectively, and 17 and 20, respectively, which form the valve 90 casing forming bores, the upper bore whereof (indicated by the numerals 17 and 20) is the larger. The die members 12 and 13 95 are formed also with the semicylindrical recesses 18 and 21, respectively, adapted for co-operation, which are adapted to serve as a seat or compartment for the annular thread forming die 22, the latter being centrally 100 apertured and formed with the screw threads 23 within said aperture. The die 22 is formed also with a plurality of lugs 24 on its upper face which are adapted to be engaged by a spanner wrench, for the 105 purpose hereinafter specified.

110 Numeral 25 indicates a cylindrical arbor member rigidly fixed in a carrier member 26 adapted to be connected with or secured in and actuated by a press of any suitable

character, said arbor having an annular enlarged portion 27 adjacent its lower end, the latter being somewhat reduced at its extremity 28. Numeral 29 indicates a cylindrical ductile metal tube of substantially uniform thickness and diameter and provided with a relatively short cylindrical reduced portion 30 at one end thereof, the latter being adapted to have screw threads 10 formed thereon by expansion into the thread forming die 22, as hereinafter described.

In the construction of my improved valve casing the tube 29 is placed in the die bores 15 with the reduced portion 30 uppermost. Thereupon, the die member 22 is arranged within the recesses 18 and 21, the threads 23 whereof being thereby arranged around and adjacent the exterior surface of the reduced 20 tube portion 30. Thereupon, the dies 12 and 13 are closed by the operation of the set screws 15, the position of the members mentioned being clearly shown in Fig. 5 of the drawing. Thereupon, the plunger arbor 25 is 25 thrust into the interior of the tube 29 for a portion only of its length, the tube being thereby expanded uniformly into the bore portion 17 and 20 by the enlargement 27 and the metal of the outer periphery of the reduced portion 30 thereof is forced into the interstices of the screw threads 23 of the die 22, thereby forming screw threads upon the outer periphery of said portion 30. The 30 condition of the tube 29 after the operation of the arbor 25 as described is clearly indicated in Fig. 4 of the drawing. Thereafter, the tube is removed from the dies 12 and 13, the thread forming die 22 is unscrewed with a spanner wrench, or otherwise, and the unfinished casing member is then provided 35 with the air passages 11, 11 and machined or finished interiorly and exteriorly to the desired finish and dimensions.

I claim:

1. A device for shaping a one piece wind instrument valve casing comprising a die member having a bore within which the valve casing is adapted to be confined during the shaping operation, said die being 45 provided also with an enlarged bore section into which the metal of the valve casing may be pressed; a screw thread forming die encompassing a portion of the valve casing; and an arbor member adapted to forcibly engage the inner wall of the valve casing for expanding and forcing the metal thereof into the enlarged bore section of the die and 50 55

into the interstices of the threads of said screw thread forming die.

2. In a device for shaping a one piece 60 wind instrument valve casing, a die member composed of a plurality of sections and having a bore within which the valve casing is adapted to be confined during the shaping operation, each die section having a recess therein adjacent one end of said bore the plurality of recesses in said die sections coöperating to form one complete recess encompassing one end of said bore; a screw thread forming die arranged within said 65 recess and encompassing a portion of the valve casing; means for clamping the die section together in operative relation; and an arbor member adapted to forcibly engage the inner wall of the valve casing for 70 expanding and forcing the metal thereof into the interstices of the threads of said screw thread forming die.

3. In a device for shaping a one piece 75 wind instrument valve casing, a die member having a bore within which the valve casing is adapted to be confined, said die having a recess encompassing one end of said bore; a screw thread forming die arranged within said recess and encompassing 80 a portion of the valve casing; and an arbor member adapted to forcibly engage the inner wall of the valve casing for expanding and forcing the metal thereof into the interstices of the threads of said thread forming 85 die, said die being provided with means adapted to receive a tool for unscrewing same from the threads formed in said valve casing.

4. In a device for shaping a one piece 90 wind instrument valve casing, a die member having a bore within which the valve casing is adapted to be confined, said die having a recess encompassing one end of said bore; a screw thread forming die arranged 95 within said recess and encompassing a portion of the valve casing; and an arbor member adapted to forcibly engage the inner wall of the valve casing for expanding and forcing the metal thereof into the interstices of the threads of said thread forming die, said die being provided with a plurality 100 of projections adapted to receive a tool for unscrewing said die from the threads formed in said casing.

In testimony whereof I have hereunto affixed my signature this 24th day of October, 1918.

EDWARD J. GULICK.
